FOREIGN PATENT DOCUMENTS

WO 2004110917 12/2004

Primary Examiner — Elizabeth Albert(74) *Attorney, Agent, or Firm* — Christine Flanagan(57) **CLAIM**

The ornamental designs for a bottle opener, as shown and described.

DESCRIPTION

FIG. 1 is a perspective view of the bottle opener showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines are for the purpose of illustrating the environment of the design only and form no part of the claimed design.

1 Claim, 4 Drawing Sheets(56)
